HEEL CONSTRUCTION FOR FLIMSY FOOT COVERINGS

Walter J. Paul, Vista, Calif.

Application April 2, 1951, Serial No. 218,853

6 Claims. (Cl. 36—10)

1

This invention relates to a foot covering of the type disclosed in the prior Patents No. 1,912,539 and No. 1,991,624 granted to Richard C. Paul. They both disclose a liner or stiffener placed in the foot covering inside its heel portion and sewed to the same along their upper edges.

In both of the patents the liner or stiffener was of sufficient depth measured from the upper edge of the foot covering, to rest upon the sole portion, and the function of the liner was to prevent the flimsy material of the heel from slipping down on the heel of the wearer. In Patent No. 1,912,539 the liner was formed with two downwardly projecting lobes, the adjacent edges of which curved upwardly on the medial vertical axis of the liner and merged into a fair-line arc to form a notch; the edges or sides of this notch converged towards each other on an acute angle. This notch was intended to give a shape that would fit to the tendon of Achilles at the wearer's heel, and to enable the heel portion to be "form-fitting." Also, the upper edge of the liner, when the liner was laid flat upon a horizontal surface, was disposed along an arc on a radius that gave it considerable curvature. These features did not cooperate as satisfactorily as expected, and it was found that the excess of material near the upper edge of the liner (due to the arc-form) had a tendency to cause the upper edge of the foot covering to displace itself backward, that is, in a rearward direction, so as to prevent the desired form-fitting effect. Furthermore, a tendency developed for the flimsy material of the heel portion in the area between the edges of the notch to crowd itself upwardly into the notch so as to produce folds of the material at the liner just above the notch and at its vertex.

The present invention has for one of its objects to overcome these objections and to produce a liner that when attached in the heel of such a foot covering enables the same to be substantially form-fitting at and around the wearer's heel, at the same time, supporting the flimsy heel in its proper elevated position.

Further objects of the invention will appear from a study of the following specification and the accompanying drawing.

The invention consists in the features of the liner and the foot covering described herein that cooperate to produce a form-fitting self supporting heel for the article.

A preferred embodiment of the invention is described in the following specification, while the broad scope of the invention is pointed out in the appended claims.

2

In the drawing:

Figure 1 is a side elevation of a foot covering of the type referred to above, showing the upper edge of the foot covering somewhat in perspective so as to better illustrate the relation of the liner that constitutes the principal element of the invention.

Figure 2 is a fragmentary view showing the heel portion of the foot covering as viewed in a vertical section on its medial vertical plane; and shows the parts in substantially the position and relation they have when the foot covering is being worn.

Figure 3 is a plan view of the liner showing the form of the same as it would appear when the liner is lying flat upon a horizontal surface.

Referring more particularly to the parts, 1 indicates a foot covering which in the present instance is formed of knit material. This foot covering is quite narrow in its vertical dimension so that when the foot is introduced into its upper opening 2 it can be worn inconspicuously in a low shoe or slipper. In accordance with my invention I provide a counter 3 operating as a stiffener or liner. It preferably has substantially the outline illustrated in Figure 3, being formed with two lobes 4 of substantially equal size and shape, and near the medial vertical axis *a—a* that passes through this liner the adjacent edges 5 of the lobes 4 incline upwardly and converge so as to form a re-entrant angle or notch 6. The vertex of this angular notch is located substantially on the axis *a—a*.

Furthermore, instead of forming the upper edge of the liner 3 along an arc having considerable curvature as in the prior patent referred to, I provide it with an upper edge 7 that is substantially straight though preferably very slightly bowed in an upper direction, somewhat as indicated in Figure 3.

Throughout the area of the completed liner I provide a plurality of perforations 8 of small size such as were shown in one of the prior patents referred to. They assist in supporting the liner in position on the wearer's heel and also prevent accumulation of perspiration on the inner side or face of the liner. These perforations are omitted from Figure 3 but are shown in Figure 2. This liner is formed of thin flexible material.

The angle formed by the converging edges 5 is sufficiently large to prevent the material crowding up as described above. I prefer to make it approximately a right angle. I have found that size of angle to be satisfactory in preventing any tendency of the material below the notch to force itself up into the notch and produce folds

on or adjacent to the notch and its edges 5. The tendency to form such folds seems to be developed from the action of the wearer's foot when walking.

Though in the two prior patents referred to the lower edges or edge of the liner extended down substantially to the position of the sole 9 of the article to support the liner and heel portion, I find that with a notch approximately ninety degrees two requirements are filled: first, to prevent forming the folds of material at the notch; and second, this wide angle will still ride on the heel tendon, and hold up the heel as though the liner had depth enough to have its lower edge rest on the sole at the heel of the article. This relation is illustrated in Figure 2, which shows the upper edge of the liner sewed into the upper edge of the foot covering by suitable stitching.

The two lobes 4 are integral with each other and the vertex of the notch between them is located about half-way down the heel line, but may be located slightly above that point somewhat as illustrated in Figure 2.

As indicated most clearly in Figure 3, when the liner is lying flat upon a substantially flat surface, the sides 5 of the angle then form a right angle with each other. Hence, when the liner is secured in the foot covering the actual angle formed between these sides 5 will be considerably smaller than a right angle.

In attaching the liner in place of course, the vertex of the notch or angle 6 should lie substantially in the medial or central front and rear plane of the foot covering.

Many other embodiments of the invention may be resorted to without departing from the spirit of the invention.

I claim as my invention, and desire to secure by Letters Patent:

1. A foot covering comprising a body of flimsy material and a counter, said body having an upper opening to receive the foot and being of relatively narrow vertical width to enable the same to be worn inconspicuously with a low shoe or slipper, and said counter including a pair of laterally extending lobes integrally connected to each other at their rear ends, said lobes having lower edges of upwardly extending arcuate configuration disposed on lines intersecting each other at the rear of said lobes to form an up-

wardly directed notch, the upper edge of said counter being secured to the upper inside heel edge of said body, and said lower edges of said lobes terminating at a height enabling said lower edges and the internal faces of said lobes to rest on the opposite outwardly and downwardly sloping heel surfaces of the wearer's foot inserted in said foot covering.

2. The device set forth in claim 1 wherein the edges of said notch are disposed with respect to each other so that at their intersection at the vertex of said notch they form substantially a right angle when said counter is placed upon a substantially flat surface.

3. The device set forth in claim 1 wherein the lowest points of the edges of said lobes are substantially midway between the upper and bottom edges of said body when said covering is folded flat about the junction of said lobes.

4. The device set forth in claim 1 wherein said lower edges of the lobes curve upwardly and rearwardly to a point of intersection well above the rearmost point of bulge of the heel of said foot.

5. The device set forth in claim 1 whereby the position of the lowest points of the lower edges of said lobes is substantially three-quarters of the distance from the top of said body to the bottom of the sole of the body when said foot covering is on the wearer's foot.

6. The device set forth in claim 1 wherein the forward edges of said lobes are of arcuate configuration curving downwardly from the upper edges of said lobes to the lowermost point of the lower edges of said lobes.

WALTER J. PAUL.
